(57) **CLAIM**

The ornamental design for an operator housing, as shown and described.

DESCRIPTION

FIG. 1 is a top, and a side perspective view of an operator housing showing my new design;

FIG. 2 is a front elevation view thereof;

FIG. 3 is a side elevational view thereof;

FIG. 4 is a side elevational view thereof showing the side opposite that shown in FIG. 3;

FIG. 5 is a top plan view thereof; and,

FIG. 6 is a bottom plan view thereof.

The broken lines are shown for illustrative purposes only and form no part of the claimed design.
